UNITED STATES PATENT OFFICE.

JOHN ASTROM, OF FORT WAYNE, INDIANA.

PUMP VALVE.

Application filed June 16, 1924. Serial No. 720,373.

To all whom it may concern:

Be it known that I, JOHN ASTROM, a citizen of the United States, and resident of Fort Wayne, in the county of Allen and State of Indiana, have invented certain new and useful Improvements in Pump Valves; and I do hereby declare that the following is a full, clear, and exact description thereof.

This invention relates to pumps and is an improvement over the pumps disclosed in my prior Patents Nos. 1,196,920, granted September 5, 1916, and 1,328,474, granted January 20, 1920.

Objects of this invention are to provide a pump in which the valve may be composed of leather or other suitable material which will not be injured by oil, or high temperature water and other fluids which frequently injure rubber valves.

Further objects are to provide a valve which is formed of pliable material and encircles the cylinder or other equivalent portion adjacent the discharge aperture, and abuts against an adjacent flat face to accurately and completely seal the discharge opening by tightly engaging the pump structure at two distinct places on opposite sides of such opening, and to provide a valve of this general type which when opened, is relieved of binding frictional engagement with the cylinder or equivalent portion upon which it is adapted to slide so that it will slide upon such portion without undue friction and wear.

Further objects are to provide a pump having an annular discharge opening which is completely sealed by a valve contacting and inherently conforming to portions of the pump on opposite sides of such annular opening, so that the discharge may be free and complete around the cylinder and so that sealing is effectively secured when the discharge ceases.

Further objects are to provide a valve which may be simply and cheaply manufactured, which will secure the maximum opening for minimum movement, and which is strong and reliable in construction.

An embodiment of the invention is shown in the accompanying drawings, in which:-

Figure 1 is a vertical sectional view through the end of a pump equipped with the valve.

Figure 2 is an end view of the valve guard ring.

Figure 3 is a view of the valve.

The pump comprises a cylinder 1 which may have a liner portion 1 and a body portion 2. Within this cylinder a piston 3 is mounted for reciprocation by any suitable means. A cylinder head 4 is secured to the cylinder body and is provided with a central inlet aperture 5 closed by means of a valve 6. The valve 6 is carried by a valve stem 7 suitably guided, as shown, and urged towards valve setting position by means of a spring 8. The inlet 9 communicates directly with the interior of the cylinder head 4 and, if desired, an air chamber 10 may also communicate with such cylinder head. The delivery end of the pump is provided with a cavity 11 encircling the projecting portion of the cylinder 1 and such cavity is provided with a discharge aperture 12. The cavity 11 may, if desired, be in communication with the cushion air chamber 13, as shown in Figure 1.

It is to be particularly noted that the inner face 14 of the cylinder head 4 is smooth and flat and is spaced a slight distance from the end of the cylinder 1 so as to provide an annular discharge opening 15 between such cylinder and such face. A flexible valve, preferably of leather, is provided and has a cylindrical portion 16 surrounding the projecting portion of the cylinder. This valve has an outwardly extending flange 17 integral with the cylindrical portion 16 and this flange seats in a flat manner against the flat surface 14 of the cylinder head.

A valve ring guard consisting of a cylindrical portion 18, an inwardly turned flange 19, and an outwardly turned flange 20 is provided with the flange 20 bearing against the flange 17 of the valve. The inwardly turned flange 19 is slidably mounted upon the cylinder 1 and the cylindrical portion 18 clears, or is out of contact with the cylindrical portion 16 of the valve, as shown in Figure 1. A helical spring 21 surrounds the valve guard and bears at one end against the flange 20 of the valve guard ring and at the other end against the face 22 of the inner wall of the cavity 11, as shown in Figure 1.

The action of the valve is extremely smooth and effective and produces little wear upon the parts. It is found that when the pressure within the cylinder increases and reaches the pressure within the annular discharge chamber 11, the grip of the cylindrical portion 16 of the valve around the cylinder as well as the pressure of the

flange 17 of the valve against the surface 14 of the cylinder head is relieved and the valve is free to move rearwardly against the action of the spring 21 and uncover 5 the annular discharge opening 15. As the speed of the piston on its forward or discharge stroke decreases, the spring 21 forces the valve closer to the surface 14 and at the moment of reversal of the piston the 10 valve is in touch with said surface and the consequent reduction of pressure within the cylinder allows the unbalanced or excess pressure in the cavity 11 to seal the valve against leakage both at the cylindrical portion 15 16 and at the flange 17.

Further, it is noted from the described 20 operation given above that although the pressure in the discharge portion of the pump may be very high that, nevertheless, prior to any movement of the valve along the cylinder, the grip of the valve is loosened by the internal pressure from the cylinder, so that at the instant the valve slides with reference to the projecting portion of 25 the cylinder, it is relatively loose thereon and free from any tight binding or gripping action.

It is apparent from the description that the valve is not called upon to widely expand or alter its shape during discharge, and that therefore an inelastic flexible material may be employed, and a material may be chosen which does not deteriorate when in contact with either oil or high temperature water or other agents which frequently injure the usual type of valves.

Although the invention has been described in considerable detail, it is to be understood that the invention may be variously embodied and is, therefore, to be limited only as claimed.

I claim:

1. In a pump, the combination of a cylinder, a cylinder head spaced from the end 45 of said cylinder and having a smooth face adjacent such end, a piston positioned within said cylinder, a valve having a cylindrical portion surrounding said cylinder and having a flange adapted to contact with the smooth surface of said cylinder head.

2. In a pump, the combination of a cylinder having a projecting portion, a piston located in said cylinder, a cylinder head having a flat surface in proximity to the

end of said cylinder, an inlet valve for said cylinder, and an outlet valve surrounding the projecting portion of said cylinder and adapted to contact with the flat face of said cylinder head. 55

3. A pump comprising a cylinder, a piston mounted therein, a cylinder head having a flat face adjacent and spaced from the end of the cylinder, said pump having an annular discharge cavity surrounding the end of the cylinder, a valve having a cylindrical portion surrounding said cylinder and having a flange adapted to contact with the flat face, a valve guard surrounding said cylindrical part of said valve and having a flange contacting with the flange of 70 said valve, and a spring urging said valve guard towards said valve. 60

4. A pump comprising a main body portion having an annular discharge cavity therein provided with an open outer end, 75 a cylinder liner carried within said body portion and projecting into said cavity, a piston mounted within said liner, a cylinder head closing the opening in said cavity and having a flat face spaced from the projecting end of said liner, and a flexible valve having a cylindrical portion mounted upon the projecting portion of said liner, and having an outwardly projecting annular flange adapted to contact with the flat face 80 of said cylinder head. 85

5. A pump comprising a main body portion having an annular discharge cavity therein provided with an open outer end, a cylinder liner carried within said body portion and projecting into said cavity, a piston mounted within said liner, a cylinder head closing the opening in said cavity and having a flat face spaced from the projecting end of said liner, a valve guard having a cylindrical portion surrounding the cylindrical portion of said valve and having an outwardly projecting flange contacting with the inner face of the flange of said valve, and a spring surrounding said valve guard 100 and pressing the flange of such valve guard against the flange of said valve. 95

In testimony that I claim the foregoing I have hereunto set my hand at Fort Wayne, in the county Allen and State of Indiana. 105

JOHN ASTROM.
